FLAME IGNITER FOR JET PROPULSION UNITS

Frank A. Parker, Jr., United States Navy

Application May 16, 1945, Serial No. 594,129

10 Claims. (Cl. 60—39.14)

(Granted under the act of March 3, 1883, as amended April 30, 1928; 370 O. G. 757)

1

This invention relates to jet propulsion units and more particularly to an improved igniting device for liquid propellants.

In one form the present invention is particularly intended for use with liquid propellants which normally do not ignite spontaneously upon contact with each other. Such liquid propellants may comprise an oxidizer such as liquid oxygen or nitric acid which is sprayed into a combustion chamber together with a fuel such as gasoline, fuel oils, hydrocarbons, aromatics and the like.

When the above propellants in combination are subjected to an intense flame they are heated sufficiently to ignite and oxidize the fuel, resulting in the desired expansion and effecting a propulsive jet from the discharge nozzle of the unit.

The present invention is particularly directed to an improved starter for liquid jet propulsion units and has as one object the provision of compact means supplying a pilot flame to positively ignite the propellants, which means is operated independently of the main fuel nozzle.

An additional object of the present invention is to provide in a jet propulsion starter assembly, combined fluid flow control means and spark producing means which may be operated to furnish the initial heat of combustion for propulsion starting purposes.

A further object is to provide an independent liquid propellant igniting and burning device continued operation of which serves to protect portions of the starter mechanism from damage by the heat of normal combustion.

It is a further object to combine in a pilot combustion supply device means for protecting said device against the products of combustion and means for automatically terminating a portion of the pilot operation upon proper ignition of the main fuel charge.

Other objects and advantages will be herein-after more fully described and for a complete understanding of the nature, scope and characteristics of this invention reference may now be had to the following description and accompanying drawings, in which latter:

Fig. 1 illustrates a schematic fuel system partially in vertical cross-section showing one embodiment of the present invention.

Fig. 2 is a schematic fuel system showing another embodiment of the present invention.

The system employed may comprise a high pressure tank 10 containing a suitable gas under very high pressure the discharge of which

through line 11 may be controlled by means of reducing valve 12. The gas under high pressure then passes to a T connection 13 where it is distributed through lines 14 and 15, as shown. Line 14 applies pressure to a main propellant fuel tank 16 while through line 15 pressure is applied to a liquid propellant or oxidizer tank 17. Discharge of propellant liquid from these tanks through lines 18 and 19 may be controlled simultaneously by electrically operated valves 20 and 21 to permit the contents to be directed into the usual liquid combining nozzle 22. A suitable electrical switch 21a may be provided so as to operate the valves 20 and 21 together.

15 The nozzle 22 discharges into an enlarged spherical combustion chamber 23, as shown, and the propellant liquids when they are ignited forcefully expand and emerge through jet propulsion nozzle 24 to provide the desired propulsive effect.

20 A T connection 25 may be provided leading a portion of the contents from the main fuel tank 16 through line 26 where its flow is controlled by means of a separate electrically controlled igniter valve 27, the operation of which may likewise be controlled by means of a suitable electrical circuit including switch 28, as shown. Fuel from valve 27 is then conducted through line 29 to an annular recess 30 in a starter valve seat housing 31.

25 The starter mechanism of the present invention comprises the valve seat housing 31 which is provided with a plurality of seat encircling apertures 32 leading from the annular recess 30 and through which liquid propellant from tank 16 is projected into the combustion chamber 23. As the fuel so supplied must be mixed with air or another oxidizer before it can be ignited for starting purposes there is provided 35 a separate motor driven blower 33 which forces air through conduit 34 into the space 35 within the valve seat housing and from the lower portion of which it emerges to mix with the liquid fuel emerging from the inwardly directed apertures 32 forming therewith a suitable combustible mixture. An inlet valve 36 having a head 37 may be employed to control the air flow in a manner hereinafter to be described.

30 In order to ignite the fuel and air mixture thus provided, a high tension electric spark may be caused to jump from the head 37 of the valve to a seat 38 thereby igniting the fuel and air mixture. This high tension current may be supplied in any desired manner as well known in the art through a suitable cable 39 which is

connected to the upper end of the stem of valve 37. This stem is mounted for vertical reciprocation in a block 40 of suitable insulating material and is surrounded by a compression spring 41 which bears against washer 42 secured on the stem and normally urges the valve into the open position as shown.

In operation, valve 12 is first opened to permit pressure to be applied to the liquid propellant in tanks 16 and 17. No propellant can pass through valves 20 and 21 since they are closed, however, liquid fuel may pass through line 26 to valve 27. Valve 27 may then be opened by the operation of switch 28 to permit fuel under pressure to flow through line 29 and emerge from the inwardly directed apertures 32 which surround the valve seat.

Simultaneously with the above described procedure the electrically operated blower 33 may be started as by means of the electrical circuit 28a whereby it will deliver air through conduit 34 so that it emerges through the angular space surrounding the valve.

Concurrently with the above a high voltage current may be supplied through conductor 39 and be caused to jump across the space from the head 37 of the valve to seat 38 effecting instantaneous ignition of the combined fuel and air mixture.

It will be apparent that the combustion thus occurring within the combustion chamber slightly increases the pressure therein, however, spring 41 is of sufficient strength to prevent the valve from being closed by the amount of pressure so created.

With the pilot flames produced and in operation as above described valves 20 and 21 may thereupon be opened by operation of electrical control switch 21a so that liquid fuel and oxidizing mixture in the desired proportions may be forced from supply chambers 16 and 17 into the discharge nozzle 22 from which they emerge into the combustion chamber 23. The liquid propellants so supplied are immediately ignited by the intense heat already existing within the combustion chamber 23 by reason of the pilot flame. The greatly increased temperature and resulting rise in pressure is now sufficient to overcome spring 41 and forces the valve head 37 upon the seat 38.

Because of the intense temperature rise which exists within the combustion chamber 23 liquid fuel is supplied to the valve seat during the entire jet operation and emerges from the apertures 32 being directed by these apertures in a spray over the valve head 37. The effect of this operation is to blanket or protect the valve head 37 from the heat, cooling the head and preventing warping or other deleterious effects as a result of this heat.

When valves 20 and 21 are closed the propellant chamber pressure drops and permits the spring loaded valve to lift from its seat. The igniter may then be operated as before and continues to operate as desired.

In the embodiment illustrated in Fig. 2 a modification of the present invention is shown wherein the igniter heretofore described may be adapted for use with a monopropellant such for example as nitromethane (CH_3NO_2). In this embodiment the nitromethane takes the place of both the fuel and the oxidizer and may be stored in a single fuel tank or there may be provided a monopropellant tank 50 and an ignitor fuel tank 51 which later may contain

either the monopropellant or a separate igniter fluid.

When separate tanks are employed the monopropellant may be led from tank 50 through line 52 controlled by valve 53 which may be remotely operated by means of switch 54. Monopropellant is thus conducted to the main fuel nozzle 22 in the manner hereinbefore described with regard to the first embodiment.

In Fig. 2 the igniter fuel tank 51 is shown connected by outlet line 55 to the igniter nozzle and the flow may be controlled by the valve 27 as was hereinbefore described with respect to the first embodiment.

In operation the device of the second embodiment, whether employing monopropellant or some other fluid for ignition purposes, conducts fuel from tank 51 to the ignition chamber where it is mixed with air entering through conduit 34 and by the means hereinbefore described is ignited to provide a pilot flame in the combustion chamber. Monopropellant subsequently injected from the main discharge nozzle may be ignited by this pilot flame. If monopropellant alone is to be used for both the ignition and main discharge jets then obviously tanks 50 and 51 may be combined.

From the foregoing description it will be apparent to those skilled in the art that various modifications thereof may be made without departing from the spirit and scope of this invention and it is desired, therefore, that the same be limited only by the scope of the appended claims.

The invention described herein may be manufactured and used by or for the Government of the United States of America for governmental purposes without the payment of any royalties thereon or therefor.

Having thus described the invention, what is claimed and desired to be secured by Letters Patent is:

1. In an apparatus for producing jet reaction motive force wherein a non-spontaneously ignitable main combustible charge is injected and burned, means for initiating ignition of said main charge comprising a combustion chamber, means for delivering a liquid fuel supply into the combustion chamber, means for delivering an oxygen supply into the combustion chamber to form an ignitable mixture with the liquid fuel supply, means in said combustion chamber for controlling the oxygen supply comprising a movable valve at the outlet from said oxygen delivery means normally biased inwardly in the open position, and means for igniting the mixture to provide an initial combustion flame for subsequent ignition of the main charge.

2. In an apparatus for producing jet reaction motive force having a combustion chamber wherein a non-spontaneously ignitable main combustible charge is injected and burned, means for initiating ignition of said main charge comprising means for delivering a liquid fuel supply into said combustion chamber, means for delivering an oxygen supply into said combustion chamber to form an ignitable mixture with the liquid fuel supply, means in said combustion chamber for controlling the oxygen supply comprising a movable valve at the outlet from said oxygen delivery means normally biased inwardly in the open position from its seat and electrical means for igniting the mixture including the movable oxygen valve whereby an electric spark is caused to jump from the valve to the adjacent valve seat.

3. In an apparatus for producing jet reaction

motive force having a combustion chamber wherein a non-spontaneously ignitable main combustible charge is injected and burned, means for initiating ignition of the said main combustible charge comprising, means for delivering a liquid fuel supply into said combustion chamber, means for delivering an oxygen supply into said combustion chamber to form an ignitable mixture with the liquid fuel supply, pressure responsive means in said chamber for interrupting the oxygen supply upon combustion of the main charge, and electrical means for igniting the initial oxygen and fuel supply mixture, the pressure responsive means also serving to interrupt the electrical means upon interruption of the oxygen supply.

4. In an apparatus for producing jet reaction motive force having a combustion chamber wherein a non-spontaneously ignitable main combustible charge is injected and burned, means for initiating ignition of the propellants comprising, a valve seat assembly in communication with said combustion chamber, means for delivering a liquid fuel supply to the valve seat through a plurality of perforations forming supply ports to said combustion chamber, means for delivering an oxygen supply to the valve seat assembly and said combustion chamber adjacent the liquid fuel supply ports, control means for interrupting the oxygen supply, the control means being responsive to the pressure of combustion of the main charge within the combustion chamber, and resilient means normally rendering the control means ineffective until combustion of the main combustible charge in the chamber.

5. In an apparatus for producing jet reaction motive force having a combustion chamber wherein a non-spontaneously ignitable liquid main combustible charge is injected and burned, means for initiating ignition of said main charge comprising, a valve seat assembly in communication with said combustion chamber having a plurality of perforations forming supply ports for delivering liquid fuel to said combustion chamber, means for leading a liquid fuel supply to the valve seat assembly, means for leading an oxygen supply to the valve seat assembly and for delivering it into said combustion chamber adjacent the liquid fuel supply ports, control means for interrupting the oxygen supply, the control means being responsive to the pressure within said combustion chamber, and resilient means normally rendering the control means ineffective until combustion of the main combustible charge in the chamber.

6. In an apparatus for producing jet reaction motive force having a combustion chamber wherein a non-spontaneously ignitable liquid main combustible charge is injected and burned, means for initiating ignition of said main charge comprising, a valve seat assembly in communication with said combustion chamber, and having a central passage and a plurality of perforations forming supply ports for delivering liquid fuel to said combustion chamber, means for leading a liquid fuel supply to said valve seat assembly, means for leading an oxygen supply to the valve seat assembly and for delivering it into the said combustion chamber adjacent the liquid fuel supply ports, control means for interrupting the oxygen supply, the control means being responsive to the pressure within said combustion chamber, resilient means normally rendering the control means ineffective until combustion of the main combustible charge in the chamber, and

electric ignition means for igniting the fuel and oxygen mixture.

7. In an apparatus for producing jet reaction motive force wherein a non-spontaneously ignitable liquid main combustible charge is injected and burned, a combustion chamber, means for delivering liquid fuel under pressure into the combustion chamber, means for delivering an oxidizer under pressure in the combustion chamber, a main mixing nozzle for combining the fuel and oxidizer into an ignitable mixture, a separate combustion initiating starter nozzle, means for supplying liquid fuel under pressure to the starter nozzle, means for forcing air through the starter nozzle, an igniter base having ports for delivering the liquid fuel and air simultaneously into the combustion chamber, an air control valve for automatically interrupting the air supply after ignition of the main charge, and resilient means preventing interruption of the air supply until ignition of the main charge.

8. In an apparatus for producing jet reaction motive force wherein non-spontaneously ignitable liquid main combustible charge is injected and burned, a combustion chamber, means for delivering liquid fuel under pressure into the combustion chamber, means for delivering an oxidizer under pressure into the combustion chamber, a main mixing nozzle for combining the fuel and oxidizer into an ignitable mixture, a separate combustion initiating starter nozzle, means for delivering a liquid fuel supply under pressure to the starter nozzle, means for supplying air under pressure to said nozzle, an igniter base having ports for delivering the liquid fuel and air simultaneously into the combustion chamber, a control valve for automatically interrupting the air supply after ignition of the main charge, resilient means preventing interruption of the air supply until ignition of the main charge, and ignition means including a movable portion of said valve for igniting the combustion initiating charge.

9. In an apparatus for producing jet reaction motive force wherein non-spontaneously ignitable liquid main combustible charge is injected and burned, means for initiating ignition of the main charge comprising, a combustion chamber having a mixing nozzle and said main charge, means for delivering a liquid fuel supply into the combustion chamber through said mixing nozzle, means for delivering an oxygen supply into the combustion chamber through the mixing nozzle, remote control means for controlling said fuel supply means and the oxygen supply means, an igniter nozzle, means for delivering an igniter liquid fuel supply into the igniter nozzle, a separate means for delivering an oxidizer supply into the igniter nozzle, remote control means for simultaneously initiating the igniter liquid fuel supply means and igniter oxidizer supply means, means responsive to the pressure in the combustion chamber for interrupting the oxidizer supply independently of the liquid fuel supply, and means for igniting the igniter liquid fuel and oxidizer supply within the combustion chamber.

10. In an apparatus for producing jet reaction motive forces wherein a nonspontaneously ignitable liquid propellant is burned, a combustion chamber, a main fuel nozzle and an igniter fuel nozzle for said chamber, means for delivering the liquid propellant to said main fuel nozzle and means for delivering the liquid propellant to said igniter fuel nozzle, said last named means including igniter means arranged to automatically

discontinue operation in response to pressure of combustion of the propellant discharged by the main fuel nozzle.
